UNITED STATES PATENT OFFICE.

LUIGI BELLANI, OF MILAN, ITALY.

MECHANICAL DESPATCH APPARATUS.

1,371,723.

Specification of Letters Patent. Patented Mar. 15, 1921.

Application filed September 24, 1918. Serial No. 255,517.

To all whom it may concern:

Be it known that I, LUIGI BELLANI, a subject of the King of Italy, residing at Milan, Kingdom of Italy, have invented certain 5 new and useful Improvements in Mechanical Despatch Apparatus, of which the following is a specification.

The invention relates to a mechanical despatch apparatus of the type which comprises 10 two carrying cables and a continuous tractor cable, constructed and arranged in such a manner as to reduce to a minimum the weight of its constituent members, as well as the time necessary for its erection and 15 mounting, all the horizontal strains being equalized by the employment of stays secured to the ground while the vertical strains are borne solely by supporting frames.

In the accompanying drawings—
20 Figure 1 is an elevation of the apparatus at a sending station.

Fig. 2 is a plan of the same.

Fig. 3 is an elevation of the apparatus at a return station.

25 Fig. 4 is a plan of the same; and

Fig. 5 is an elevation of one of the intermediate supports having a carriage of the Valtellina type for working with a non-automatic continuous movement.

30 The apparatus at the sending station consists of a solid metal frame carrying the various mechanisms, that is to say, a main pulley A with its shaft B and supports therefor, a counter pulley C and its axle, a 35 bevel gear D, a speed reducer E, a universal joint F provided with a hand-operated controlling lever G, a pedal brake H and a motor M. The said apparatus is placed on the ground and is fixed to the earth by means of

40 pointed feet or pegs L without any special foundations and is then firmly secured by means of stays R formed of metal cord fixed by means of iron stakes driven into the ground and provided with turnbuckles T to 45 allow of regulating the tension of the cords.

The station apparatus is also provided with guide rollers N for the tractor-cable which, consequently can assume any required inclination, and with grips O for the carrying 50 cables.

The type and the arrangement of the motor group at the station can be varied, but the arrangement of pulleys must remain unchanged in order to insure the adherence of 55 the tractor cable as well as the system of staying the iron frame. The entire arrange-

ment, including the iron frame, is made as light as possible and is designed to be easily taken apart for the purpose of facilitating transport and erection. The sending station 60 can be located either at the lower or at the upper end of the trolley line.

The apparatus at the return station consists simply of an iron frame carrying the return pulley P with its axle. This frame, 65 having two feet provided with pegs Q driven into the ground, is kept rigid and in proper position with respect to the line by means of stays R of metal cord attached to stakes S driven into the ground. Each stay is provided with a turnbuckle or regulating device T. The apparatus carries the grips U of the carrying cables and the guides V for the tractor-cable.

The intermediate supports are each 75 formed of an iron post X composed of sections or members of equal length connected by means of screw-joints. At the top of the support the cross bar Z carries the hinged supports a on which bear the carrying 80 cables.

The lower cross-bar b carries the pulleys c on which rests the tractor-cable guided by the iron pieces d. The post X is fixed to the ground by means of the peg e and secured 85 by means of stays f fixed to stakes g and provided with turnbuckles h. The type of support adopted allows of easily altering the height by varying the number of sections of which the post X is composed. It 90 is thus always possible to place the support in proper position relatively to the line in order that the pressure exerted by the stay cords may not be felt by the post except by compression.

The carrying cables are securely fixed in the upper station of the aerial transport line, being here shown as wound upon a drum i fixed to an iron stake l driven into the ground.

In the lower station the carrying cables are wound upon the drums m which are turned by means of the lever n until the required tension has been obtained. Here, also, the drums m rest upon stakes o fixed 105 in the ground. When the required tension has been attained, the cables are fixed in the grips O. Along the line the carrying cables are suspended from the intermediate supports by means of the hinged supports a.

110 The tractor cable follows the same course as the carrying cables. In the sending sta-

tion it passes around the main pulley and over the auxiliary pulley, thus forming a kind of 8, this being necessary in order to obtain sufficient adherence. In the return 5 station the same cable passes around the pulley P and along the line it rests upon the rollers c of the intermediate supports.

The carriages each consist of a wheel p fixed to an arm q, two rings r between which 10 is gripped the traction cable, a hook s and chains t to which is attached the platform u on which are placed the materials to be transported. The form of the platform may vary to suit the nature and bulk of the 15 said materials; also the load may be distributed over several carriages arranged tandem fashion. The loaded carriages always travel along one branch of the line only, the number thereof depending on the length 20 of the line. On the opposite branch travel an equal number of empty carriages, and at each arrival of the carriages at the stations the motor is stopped in order to effect the loading and unloading operations which are 25 accomplished with great rapidity.

Having now particularly described and ascertained the nature of my said invention and in what manner the same is to be performed, I declare that what I claim is:

30 1. In an aerial despatch system, the combination of a sending apparatus and a return apparatus, each comprising a vertical frame supported in the ground; tractor and carrying cables connecting said frames; 35 operating means for the tractor cable; a drum located in rear of each said frame, one drum being fixed and the carrying cables being secured at one end to said fixed drum and being wound at the other end upon the 40 other drum; means for turning the last-named drum to adjust the tension of the carrying cables; grips for securing said carrying cables directly to said frames after 45 their tension has been adjusted; and stakes to which said drums are directly attached anchored in the ground.

2. In an aerial despatch system, the combination of a sending apparatus and a return apparatus, each comprising a vertical frame supported in the ground; a main pulley and a counter pulley mounted in the sending apparatus frame; a return pulley mounted in the return apparatus frame; an endless tractor cable passing directly around the return pulley and in an 8-shaped path 50 around the main and counter pulleys; a motor adjacent the sending apparatus frame; gearing between the motor and the main pulley, to drive the latter from the former; means for controlling the motor drive; 55 carrying cables connecting said frames; means for adjusting the tension of the carrying cables; and means for securing said carrying cables to said frames after their tension has been adjusted. 65

3. In an aerial despatch system, the combination of a sending apparatus and a return apparatus, each comprising a vertical frame supported in the ground; a main pulley and a counter pulley mounted in the 70 sending apparatus frame; a return pulley mounted in the return apparatus frame; an endless tractor cable passing directly around the return pulley and in an 8-shaped path around the main and counter pulleys; 75 a motor adjacent the sending apparatus frame; gearing between the motor and the main pulley, to drive the latter from the former; means for controlling the motor drive; carrying cables connecting said 80 frames; a drum located in rear of each said frame, the carrying cables being fixed at one end to one of the drums and being wound at the other end upon the other drum; means for turning the last-named 85 drum to adjust the tension of the carrying cables; grips for securing said carrying cables to said frames after their tension has been adjusted; and securing means for said drums anchored in the ground. 90

In testimony whereof I affix my signature.
LUIGI BELLANI.
